BACKPLATE FOR FURNITURE HARDWARE

James R. Deadrick, Winston-Salem, N.C., assignor to Stewart-Warner Corporation, Chicago, Ill., a corporation of Virginia

Filed Oct. 16, 1961, Ser. No. 67,108

Term of patent 14 years

(Cl. D50—6)

FIG. 2

FIG. 1

FIG. 1 is a front elevational view of a backplate for furniture hardware showing my new design; and

FIG. 2 is a sectional view as generally seen from line 2—2 of FIG. 1.

The rear not shown is substantially plain.

I claim:

The ornamental design for a backplate for furniture hardware, substantially as shown and described.
